PUMP

Continuation of application Serial No. 88,327, filed February 15, 1926. This application filed December 15, 1927. Serial No. 240,316.

In the construction of centrifugal pumps it is common practice to mount the impellers upon a round steel shaft by means of the ordinary gib-head key. In this construction it is necessary to provide a sufficiently large bore in the impeller to permit the shaft to slide freely therethrough, and consequently when the impeller is properly positioned and the key driven in tightly the desired concentric relation of the impeller to the shaft 10 is destroyed by forcing the shaft away from the bearing surface on the side of the key and into close contact with the impeller on the side remote from the key.

Also when the load of driving is applied the force acting upon the driving shaft will urge it into contact with the impeller upon one side of the key with a corresponding separation from the impeller upon the opposite 20 side of the key thereby creating an eccentric relationship between the driving shaft and impeller.

This offsetting of the impeller relative to the shaft on which it is mounted obviously unbalances the impeller so that balancing of the same is required after the impellers are mounted on the shaft. Also, since the impeller is offset relative to the shaft it is also offset relative to the axis of the neck of the 30 bowl in which it operates. It is necessary, therefore, to provide a bowl having a neck somewhat larger than the impeller to permit the free rotation of the impeller therein.

Because of this somewhat eccentric mounting of the impeller on the shaft considerable hand fitting is required in assembling the parts, and non-interchangeable parts must be used. Furthermore, in this construction the shaft should be of steel to carry the load and 40 consequently will rust in the water being pumped. When rusted, the whole shaft must be replaced.

It is one object of my invention to provide a construction wherein the above mentioned difficulties may be satisfactorily over-

come and the impellers accurately and concentrically mounted in the several bowls and so maintained in concentric relation thereto regardless of whether or not the shaft is concentric with the impellers, thereby eliminating the necessity of subsequent balancing and hand fitting as now required, or, in other words, to provide a journal surface for the impeller to rotate upon that is entirely separate from the driving means and which will maintain its concentric position with the impeller whether or not the driving shaft is concentric with the impeller. 50 55

It is another object of the invention to provide a structure wherein the pump bowl neck 60 may be made in its normal size and still provide the required clearance between it and the impeller, whereby to reduce leakage.

It is still another object of the invention to provide a structure wherein a non-corrosive material may be used for that portion of the shaft carrying the impellers and wherein the impellers may be mounted on the shaft 65 without the use of a key if so desired.

Finally it is an object of the invention to 70 provide a structure of the character indicated wherein a means is provided for spacing the several impellers and supporting the same, and closing the supporting shaft off from the water being pumped so that material for the 75 shaft such as steel may be used without danger of corroding.

In the drawing:

Figure 1 is a longitudinal section through a pump structure embodying my invention. 80

Figure 2 is a section on line 2-2 of Figure 1.

Figure 3 is a section on line 3-3 of Figure 1.

Figure 4 is a sectional view through a portion of a pump structure showing another embodiment of my invention. 85

Figure 5 is a detail illustration showing a means for securing a positive driving connection between the sleeve and impeller. 90

Referring more particularly to the drawing, I show at 1 a portion of a shaft hexagonal in transverse cross-section, having one end upset as at 2 and the other end cylindrical in form as at 3 and threaded as at 4 and 5.

At 6 I show an impeller broached as at 7 to engage the shaft part 1, and having annular shoulders formed in each end thereof and concentrically positioned relative to its axis of rotation as shown at 8 and 9 respectively.

Between each two impellers is shown a sleeve 10. This sleeve 10 is somewhat larger than the shaft part 1 and completely encloses the same, and fits snugly into the opposing shoulders 8 and 9 of the two impellers. A sleeve 10 is also shown inserted between the upset end 2 of the shaft part 1 and the shoulder 8 of the lowermost impeller, and another sleeve 10 is shown mounted upon the uppermost impeller. On this upper sleeve 10 is seated a nut 11 which is screwed into place on the threaded part 3 of the shaft.

It may now be clearly seen that by providing sleeves 10 of uniform length the impellers and sleeves are each interchangeable and may be assembled as they come to hand, and merely slipped on to the shaft without the use of a key of any kind. The impellers and shaft must of necessity rotate as a unit, and they are securely bound together with the sleeves on the shaft by the upset end 2 on shaft part 1 and the lock nut 11, this binding together of the impellers and sleeves effecting a positive driving connection between them.

In the construction hereinbefore described the several impellers are concentrically mounted in their respective bowls and when once placed in position with the sleeves 10 driven into place no further adjustment is required. The bowl 12 may be provided with a neck 13 sufficiently large to permit the free rotation of the impeller, but it need not be oversize as in the pumps heretofore constructed.

Since it is, in practical work, necessary to provide some little spacing between the impeller and the drive shaft in order to render the impeller slidably on the drive shaft, it necessarily follows that although the shaft and impeller may be concentric when at rest, when a polygonal shaft of the type described is used, this concentric relationship is immediately destroyed when power is applied to the shaft since it is of necessity forced into contact with the impeller hub at one point and away therefrom at another.

Since the water is entirely shut off from the shaft part 1 it is effectually prevented from rusting, and consequently provides a durable construction.

In the embodiment shown in Figure 4, it is shown that this construction may also be used with a round shaft if so desired by using

a Woodruff key 14 that does not drive the shaft against the side of the impeller but merely fits tightly against the sides of the keyway 15 to secure a proper driving connection between impeller and shaft. In this construction the action is similar to that in which a polygonal shaft is used since the shaft must, under power, of necessity be forced toward the impeller hub at one point and away from the same at another point on opposite sides of the key. If a key is driven in in such a manner as to secure a tight fit between shaft and impeller then an eccentric relation would be had, but the concentric relation of impeller and bowl would not be destroyed, because the impeller must run true in the journal surface provided in the bowl neck 13.

The sleeves 10 clearly perform several important functions. They space the several impellers to which they may be secured in any suitable manner. They protect the shaft from the corrosive action of the water being pumped. They may be made of non-corrosive material and they function as bearings. But their most important function is to co-operate with the bearings and the bowls to maintain the impellers in concentric relation to the bowl necks irrespective of the exact relation between the shaft and the impellers. This desired cooperation can only be secured, of course, if a correct driving connection is established between the sleeve and impeller. This connection may be secured as described, or in other ways such as notching the sleeve as at 16 and providing a key 17 long enough to engage the notches. The engaging notch and key construction 16-17 is preferably used merely to prevent slippage between the impeller and sleeve.

It is to be understood, of course, that while I have herein shown and described the preferred embodiment of my invention, changes in form, construction, and method of assembly and operation may be made within the scope of the appended claims.

I claim:

1. In combination, a pump bowl having a bearing therein, a sleeve revolvably mounted in the bearing, a drive shaft passing through the sleeve in spaced relation thereto, an impeller revolvably mounted in the bowl in axial alignment with the sleeve, a driving and aligning connection between the impeller and sleeve, and driving means inserted between the impeller and shaft.

2. In combination, a pump bowl having a bearing therein, a sleeve revolvably mounted in the bearing, a drive shaft passing through the sleeve in spaced relation thereto, an impeller revolvably mounted in the bowl in axial alignment with the sleeve and having a recess formed in the end thereof in concentric relation to its axis of rotation, one end of the adjacent sleeve being fitted into said recess

to effect a driving connection with said impeller, and driving means inserted between the impeller and shaft.

3. In combination, a pump bowl having a bearing therein, a sleeve revolvably mounted in the bearing, an impeller journaled in the bowl in axial alignment with the sleeve, a driving connection between the sleeve and impeller, an auxiliary driving means inserted 10 between the sleeve and impeller, and driving means for the impeller.
